UNITED STATES PATENT OFFICE.

AUGUST PETERSON, OF TRIUMPH, MINNESOTA.

COMBINED SLED AND BOX.

Application filed April 5, 1922. Serial No. 549,712.

To all whom it may concern:

Be it known that I, AUGUST PETERSON, a citizen of the United States, residing at Triumph, in the county of Martin and State 5 of Minnesota, have invented certain new and useful Improvements in Combined Sleds and Boxes; and I do hereby declare the following to be a full, clear, and exact description of the invention, such as will 10 enable others skilled in the art to which it appertains to make and use the same.

The primary object of this invention is the provision of an article which may be constructed from a single blank of sheet 15 material, preferably metal, and which will combine a box and a sled, and which will obviate the use of separate parts outside of fastening means, the article being of the nature of a toy which may be drawn over 20 a supporting surface in substantially the same manner as a sled or analogous article.

Other objects and advantages will be apparent and suggest themselves as the nature of the invention is understood.

25 While the drawings illustrate an embodiment of the invention it is to be understood that in adapting the same to meet different conditions and requirements, various changes in the form, proportion and minor 30 details of construction may be resorted to without departing from the nature of the invention.

Referring to the accompanying drawings forming a part of the application,

35 Figure 1 is a top plan view of a combined sled and box embodying the invention, the dotted lines indicating the outline of the blank from which the article is formed,

Figure 2 is a side view thereof, and

40 Figure 3 a cross section on the line 3—3 of Figure 1.

Corresponding and like parts are referred to in the following description and designated in the several views of the drawings by like reference characters.

45 As herein before stated, the article is constructed of a single sheet of thin material, such as metal, which may be of any required gage best adapted according to the size of 50 the article when completed. The sheet metal blank is preferably of oblong form and has portions partly cut therefrom and bent to provide the elements of the box and the runners and connections of the sled. Portions 55 1 are cut from an end of the blank and are discarded. These cut away portions

are of quadrant shape. Triangular shaped portions 2 are likewise cut from the blank and are considered as waste, since they form no part of the completed article. The flaps 60 3 comprised between the cut away portions 1 and 2 constitute sections of the sides of the box. The part 4 forward of a straight line connecting the cut away portions 2 constitute the front of the box, the same being 65 bent upwardly on the dotted line connecting the cut away portions 2. The flaps 3 are bent on the dotted lines connecting the cut away portions 1 and 2. Triangular portions 5 are cut away from the opposite end portions of the blank and these cut away portions 70 5 correspond with the cut away portions 2, the cut away portions 2 and 5 on the same side of the blank being reversely disposed. Opposite side portions 6 are partly 75 cut from the blank and are bent upwardly on the dotted lines connecting the cut away portions 1, 2 and 5, whereby to form the sides of the box. The part 7 in the rear of the cut away portions 5 is adapted to be bent 80 upwardly on the dotted line connecting said cut away portions to form the back of the box. The flaps 8 at opposite ends of the part 7 and in line with the cut away portions 5 are adapted to be bent on the dotted lines 85 and constitute sections of the sides of the box. The central portion 9 of the blank, having the parts 4 and 7 at opposite ends and the parts 6 at opposite sides, constitutes the bottom of the box and the bed of the 90 sled. Short transverse slits 10 are formed in the corner portions of the part 9 and are adapted to receive tongues 11 at the ends of the brace sections 12 adjacent the cut away portions 2 and 5. The parts 13, 95 adjacent the ends of the side sections 6, form connecting means between the part 9 and marginal portions 14 forming the runners of the sled. The marginal portion 15 adjacent the front section 4 constitutes a part of the 100 side marginal portions 14 and serves as a cross piece for connecting the front ends of the runners.

The blank, being formed substantially in the manner stated, is bent on the dotted 105 lines, the tongues 11 of the brace sections 12 passing through the cuts 10 and bent to retain the parts in position. The end portions of the parts 3, 6 and 8 overlap, as indicated most clearly in Figure 1, and the 110 overlapping portions are secured by means of rivets or in any preferred way. The top

edges of the ends and sides are bent, as indicated at 16, to stiffen and reinforce the parts and prevent a sharp edge which would be liable to cut the hand.

5. What is claimed is:

A combined sled and box formed from a single blank of material, the same having portions cut therefrom and discarded and other portions partly cut therefrom and 10 bent to form runners, a cross piece connecting the front ends of the runners, a bottom, a front, a back, and sides, the front and back each having opposed flaps which flaps form parts of the sides and the ends of which 15 overlap and are secured to corresponding ends of the sides, connecting portions intermediate the runners and bottom and disposed inwardly of the ends of the bottom, said connecting portions of a length equal 20 to the length of said flaps; triangular portions formed on the connecting portions by

the cutting away of certain of the discarded portions, said triangular portions bent and disposed beneath the bottom and having tongues passing through slots in the corner portions of the bottom, the projecting ends of the tongues being bent to retain the parts in the located position, and said triangular braces serving to strengthen the connecting portions and hold them in proper position 30 relative to the bottom, said flaps being of a length equal to the distance between the bottom and the runners, whereby a box of the maximum length is obtained from a sheet of metal of given size, and the amount of metal discarded is reduced to a minimum. 35

In testimony whereof I affix my signature in presence of two witnesses.

AUGUST PETERSON.
